UNITED STATES PATENT OFFICE.

LEONARD JOSEPH CLOSSEY, OF MONTPELIER, VERMONT.

PNEUMATIC HAMMER.

SPECIFICATION forming part of Letters Patent No. 777,368, dated December 13, 1904.

Application filed February 20, 1904. Serial No. 194,492. (No model.)

To all whom it may concern:

Be it known that I, LEONARD JOSEPH CLOSSEY, a citizen of the United States, and a resident of Montpelier, in the county of Washington and State of Vermont, have invented a new and Improved Pneumatic Hammer, of which the following is a full, clear, and exact description.

This invention relates to improvements in pneumatic hammers, the object being to provide a hammer of this character that will be simple in construction, positive in its action, and having no parts liable to get out of order.

I will describe a pneumatic hammer embodying my invention and then point out the novel features in the appended claims.

Reference is to be had to the accompanying drawings, forming a part of this specification, in which similar characters of reference indicate corresponding parts in all the figures.

Figure 1 is a longitudinal section of a pneumatic hammer embodying my invention. Fig. 2 is a section thereof, showing the controlling valve in reverse position to that of Fig. 1. Fig. 3 is an end view of the cylinder, and Fig. 4 is a section on the line 4-4 of Fig. 3.

Referring to the drawings, 5 designates the cylinder of the hammer, in the lower end of which is secured a sleeve 6, through which the reduced end 7 of the hammer 8 slides with practically air-tight connection.

Removably connected to the lower end of the cylinder 5 is a tubular nose-piece 9, in which is removably placed a bushing 10, it being removable, so that should the sleeve become worn it may be readily taken out and a new one put in its place. Arranged between the bushing 10 and the sleeve 6 is a yielding washer 11. The nose-piece is held from accidental rotary movement relative to the cylinder by means of a pin 12, movable in a longitudinal opening formed in the wall of the cylinder and pressed outward by means of a spring 13 to engage in a perforation 14 in the flange 15 of the nose-piece, and this opening 14 has an outward opening 16, through which a wire or other suitable instrument may be passed to force the spring-pressed pin back

and out of the opening 14 when it is desired to remove the nose-piece.

Surrounding the upper end of the cylinder and engaging removably therewith is a collar 17, against which the lower end of a cap 18 engages, the said cap having screw-thread engagement with the cylinder, and to prevent accidental detachment of the cap I employ a pin 19, movable in a perforation in the cap and pressed outward by means of a spring 20, similarly to the locking device first described, this pin being designed to engage in a perforation formed in the collar 17 and having an outward opening 21, through which an instrument may be passed to force the pin out of the perforation in the collar when it is desired to remove the cap. The cap is provided with a handle 22, which, as here shown, has screw-thread engagement with an upwardly-extended boss 31 on the cap, and in this boss is an air-chamber 23, communicating with the interior of the cylinder through an opening 24, at the upper portion of which is a valve-seat for receiving a valve 25, having an outwardly-extended stem 26, provided at its end with a finger-piece 27. The valve 25 is held yieldingly against its seat by means of a spring 28 engaging at one end with a bushing 29, through which the stem 26 passes, the said bushing being engaged in the boss having the chamber 23, and the other end of said spring engages on the valve 25.

Leading into the air-chamber 23 is a nipple 30, with which a flexible tube leading from a suitable supply of compressed air is to be connected. It will be seen that the nipple passes through an opening in the annular portion of the handle 22 and then has screw-thread engagement in the boss 31. By this arrangement air will be prevented from leaking out around the thread connection between the boss and the handle.

The valve for controlling the inlet and exhaust for operating the hammer 8 in opposite directions comprises a sleeve 32, on the upper end of which is a head 33, which passes partly into the upper portion of the cylinder, and removably placed on the inner end of the sleeve

is a collar 34, this collar resting on an interior annular shoulder 35, formed in the cylinder, thus preventing inward movement of the valve mechanism, and an outward movement is prevented by the cap 18 engaging with the head 33. Around the head 33 the cap is provided with an interior exhaust-chamber 36, from which exhaust-ports 37 lead. The interior of the sleeve 32 is divided at about the center by a partition 38. Above the partition 38 the sleeve is provided with an annular channel 39, having ports 40 leading into the interior of the sleeve 32, and below the partition 38 the said sleeve has an annular channel 41, having port communication 42 with the interior of the sleeve. Mounted on the sleeve is the movable member of the controlling-valve. This member consists of a ring 43, mounted to slide between the head 33 and the collar 34. The interior of this ring is provided with an annular port or channel 44, designed to be moved at certain times into register with the channel 39 of the sleeve, and below this interior channel 44 the ring is provided with another interior annular channel 45, which communicates through ports 46 with an exterior annular chamber 47, concentric with the channel 45. These two interior channels of the ring communicate one with the other through a series of ports 48.

In the operation, assuming the parts to be in the position shown in Fig. 1—that is, with the hammer in its lower position—the lower channel at the interior of the ring 43 will be in register with the upper interior channel of the sleeve 32, so that when the valve 25 is opened the air will pass out through the ports 40 into an annular channel 49, formed in the upper portion of the cylinder 5, and will then pass downward through a port or ports 50, formed in the wall of the cylinder and communicating with the interior thereof at the lower end. Air passing through the port or ports 50 will engage against the lower side of the hammer and force the hammer upward. When the hammer is raised about one inch, the exhaust will occur through a longitudinal port 51, formed in the wall of the cylinder. About one-half of this exhaust will pass out through the ports 37, while the other portion will pass through a port or ports 52 to the upper side of the ring-valve, throwing the same downward until the upper ends of the ports 50 are opened, permitting the air to escape. When these ports 50 are opened, the channels on the inside of the ring and the outside of the sleeve are together evenly or in register and the channel on the outside of the ring is closed. The air comes now from the first channel in the sleeve into the first channel in the ring, then through the ports 48 into the second channel in the ring, and from there returns into the second channel in the sleeve, thence passing

through the ports 42 and impinging on the upper end of the hammer, thus forcing the hammer downward. When the hammer is forced down one inch, (1") a portion of the air exhausts through a port or ports 53 into the chamber 36 and the remainder of the air passes inward through a port 54, communicating with the port 53 and underneath the ring, thus forcing it upward until the air finally exhausts through ports 50^a. In building the hammer it will be necessary to have the exhaust occur when the hammer 8 is raised or lowered from one-half inch to four inches, according to the size and use of the tool.

Having thus described my invention, I claim as new and desire to secure by Letters Patent—

1. In a pneumatic hammer, a cylinder, a nose-piece removably engaging with the end thereof, automatic means for locking the nose-piece to the cylinder, a bushing in the nose-piece, a collar in the cylinder, and a flexible bushing arranged between the bushing and 85 collar.

2. A pneumatic hammer comprising a cylinder, a hammer arranged to reciprocate therein, a cap on the cylinder provided with a threaded boss having an air-chamber communicating with the interior of the cylinder, a handle having a threaded annular portion for engaging with said boss, the said annular portion having a lateral opening, a valve for controlling communication between the air-chamber and cylinder and having an outwardly-extended stem, a spring on the stem for holding the valve yieldingly against its seat, a nipple extended through the opening in the annular portion of the handle and having screw-threaded engagement with said boss, the said nipple communicating with the chamber in the boss, and a valve for controlling the passage of air to opposite ends of the hammer.

3. An automatic hammer comprising a cylinder, a cap thereon having an air-chamber for receiving air from the source of supply, the said chamber communicating with the cylinder, a sleeve arranged in the upper end of the cylinder provided with a transverse partition and having a plurality of ports at opposite sides of the partition for communicating with the ports leading into the cylinder, and a ring-valve movable lengthwise on the 115 sleeve for automatically controlling the ports.

4. A pneumatic hammer comprising a cylinder, a cap arranged thereon and having an exhaust-chamber, ports leading through the wall of the cylinder, certain of said ports communicating with the exhaust-chamber, a sleeve arranged in the cylinder, the said sleeve being closed at about its center by means of a partition, annular channels on the outer side of said sleeve and having port communication with the interior of the sleeve at oppo-

site sides of the partition, a ring-valve movable on the sleeve and having two interior communicating channels, and an exterior channel having communication with one of 5 the interior channels, and a collar removably engaging with the inner end of the sleeve.

In testimony whereof I have signed my name

to this specification in the presence of two subscribing witnesses.

LEONARD JOSEPH CLOSSEY.
